[57] CLAIM

The ornamental design for a bottle, as shown and described.

DESCRIPTION

FIG. 1 is a front elevational view of a bottle embodying my new design;

FIG. 2 is a top plan view thereof;

FIG. 3 is a right side elevational view thereof; and

FIG. 4 is a bottom plan view thereof.

The rear elevational and left side elevational views are not shown, and are essentially mirror images of the front elevational and right side elevational views shown in FIGS. 1 and 3, respectively.
